UNITED STATES PATENT OFFICE.

EDGAR B. BADLAM, OF SAN FRANCISCO, CALIFORNIA.

HYDROCARBON-BURNER.

SPECIFICATION forming part of Letters Patent No. 752,193, dated February 16, 1904.

Application filed April 7, 1903. Serial No. 151,533. (No model.)

To all whom it may concern:

Be it known that I, EDGAR B. BADLAM, a citizen of the United States, residing in the city and county of San Francisco, State of California, have invented an Improvement in Hydrocarbon-Burners; and I hereby declare the following to be a full, clear, and exact description of the same.

My invention relates to improvements in apparatus for the combustion of liquid hydrocarbons.

It consists in an apparatus by which the temperature of the fluid is gradually raised during its progress from the point of admission to a point where it is finally subjected to the highest degree of heat just before being delivered to the burner-injector in the form of a dry highly-heated gas.

My invention also comprises details of construction which will be more fully explained by reference to the accompanying drawings, in which—

Figure 1 is a vertical section of the apparatus. Fig. 2 is a plan, a part of the distributer.

My apparatus is especially designed for the combustion of liquid hydrocarbons of any description—such as gasolene, naphtha, coal-oil, &c.—so as to vaporize and burn them without the formation of carbon deposit in retort or coils. In order to effect this result, the liquid hydrocarbon should not be vaporized in long uniformly-heated coils or in spacious heated retorts, the inlets or outlets of which are virtually of the same degree of heat.

In my invention, A is a central chamber of any desired size and shape. In the present case I have shown it vertically disposed, and the apparatus as here constructed is very suitable for heating boilers for engine-propelled vehicles or for any similar or other purpose.

2 is an inlet tube or passage, and 3 is a needle valve or jet through which the gas is discharged into the tube 2, and thence directed into the central vertical tubular chamber A. The liquid from which the gas is produced is admitted through a suitable valve 4 into a pipe 5. This pipe extends upward alongside and at a suitable distance away from the central combining-chamber A, thence it coils around the outside of said chamber a sufficient

number of turns, as shown at 6. In the present case I have shown the upper part of the chamber expanded into a pan A' of considerable diameter, around which the coils 6 are bent. These coils rise gradually up to the top 55 or just above the top of the chamber A', and thence the pipe bends downward and connects with the jet-tube 3.

In the upper part of the tubular chamber A or the pan A', as here shown, is fixed a distributor, the object of which is to direct the inflammable gas as it escapes from the upper part of the chamber so as to more intensely heat the upper part of the coil and to also direct the heat against the part to which it is to 65 be ultimately applied. This distributor is adjustable up or down to suit the character of the hydrocarbon used, or the coils might be movable and the distributor stationary. As here shown, this distributor consists of radially-disposed vanes, which are bent more or less, like the blades of a propeller-fan or windmill, as at 8. The gas, ready for combustion, rising through the chamber A A', strikes these vanes and is diverted upwardly and outwardly 70 in such a manner that when ignited an intense heat is directed upon the uppermost member of the coil. The gas also passes through between the vanes and upwardly against the part to be heated in spiral or vortex-like manner 75 or vertically, if so desired.

9 is a gauze screen through which the gas passes before ignition and which may be placed either below or above the distributor. The form of the distributor and the angle at which 80 the vanes stand are well shown, and their position relative to the gauze screen will depend upon the character of the hydrocarbon which is used, as gasolene or coal-oil, and the manner of distributing the fire that may be desired. The operation of this part will then be as follows: The hydrocarbon having been admitted through the valve 4, previously described, passes through the pipe and into the first lower portion of the coil. The coil, having been previously heated by a pilot-light or a preliminary heating-pan, will be sufficiently warm to partially vaporize the liquid and produce sufficient gas to commence operations. The apparatus being heated, the radiant heat 90

therefrom will first act upon the lower portion of the coil and raise the temperature of the liquid, eventually changing it into vapor, and as it passes around the coil it will be in condition when it reaches the upper turns of the coil to be converted into a hot dry gas by the impinging of the flame which is at this point thrown directly upon it. Thence the pipe bends abruptly downward and connects with the burner-jet, as previously described. In order to first commence the operation, I have shown a pan 10 fixed below the coil and surrounding the tube. In the bottom of this pan may be fixed any fibrous or absorbent material, such as asbestos, and a portion of inflammable liquid having been placed therein and ignited the heat will be sufficient to raise the temperature of the coil for the preliminary operation. Through this annular pan air-tubes 11 pass and provide sufficient air for combustion. Above the pan I have shown a pilot-burner 12^a, which is curved around beneath the coils, and a pipe 12, connecting with this burner, is adapted to receive a portion of the gas from the coil through a branch pipe, as at 13. The passage from these pipes is controlled by a valve, as at 14, and when the main fire is not in use a small pilot-fire can be maintained by means of this device which will maintain a sufficient heat in the coil to be in readiness for operation whenever the main burner is to be again operated. The burner proper is operative practically without the pilot-burner.

The distributor 8 is here shown as having a central support, as at 15. This support may be a rod; but I have here shown it as a hollow tube open at the bottom to admit air or an inflammable vapor or gas which may be admitted, so as to pass up through and be ignited at the top, as before described.

16 is a pipe to drain off any liquid which may collect within the chamber A.

In the drawings two methods are shown for adjusting the distributor vertically. One of these methods includes the turning of a plug 30, which screws into the bottom of the chamber A and carries the tube 15, whereby when the plug is screwed up or down the distributor is moved and its position adjusted. The second method includes the use of the nuts 32 at the top of the tube 15 and between which the distributor-vanes are clamped. Ordinarily when the apparatus is first set up the position of the distributor with relation to the screw-plug 30 at the bottom of the chamber will be determined by means of said nuts. After that any adjustment may be made by moving the screw-plug at the bottom.

Having thus described my invention, what I claim, and desire to secure by Letters Patent, is—

1. A hydrocarbon-burner consisting of a central combining-chamber, a coil surrounding the upper part thereof, means for admitting the hydrocarbon into the lower part of

the coil, means for delivering the gas through a jet into the said chamber, and a device including a disk having radial peripheral vanes whereby the gas ignited at the upper part of the chamber is directed against the upper part of the coil. 70

2. An apparatus for vaporizing and burning liquid hydrocarbon consisting of a central vertically-disposed chamber having an expanded upper portion, a coil of pipe, the lower portion of which surrounds the chamber and the upper portion is exposed above the top of the chamber, a device including a disk having radial peripheral vanes by which the combustible gases escaping from the top of the chamber are directed against the upper portion of the coil, a valve-controlled pipe connecting the source of supply with the lower part of the coil around the chamber by which the temperature of the hydrocarbon fluid is gradually raised, the heating being completed during the passage through the upper and directly-exposed part of the coil, a pipe leading from said upper part of the coil down to the delivery-jet, and means for directing said jet into the central chamber. 80 85 90

3. The combination in a hydrocarbon vaporizer and burner of a vertically-disposed central mixing-chamber having an inlet and jet located at the lower part, and an expanded upper portion, a coil surrounding said chamber having its upper portion exposed above the expanded top, means including a disk having radial peripheral means for directing the heat against the upper portion of the coil, connections between said upper portion of the coil and the inlet, and an annular pan located below the coil having air-pipes extending through its bottom, said pan serving as a preliminary heater. 100 105

4. The combination in a hydrocarbon-burner of a vertical mixing-chamber having an inlet-jet at the lower part, an expanded upper portion, a coil surrounding said chamber, having its upper portion exposed above the top, means for admitting the hydrocarbon to the lower part of the coil, means for conducting the resultant gas from the upper part of the coil to the inlet, a distributor consisting of a disk having radial peripheral vanes through which the combustible gas escapes and by which it is directed against the upper part of the coil. 110 115

5. The combination in a hydrocarbon-burner of a vertical mixing-chamber having an inlet-jet at the lower part, and discharge at the top, a coil surrounding said chamber, having its upper portion exposed above the top, means for admitting the hydrocarbon to the lower part of the coil, means for conducting the resultant gas from the upper part of the coil to the mixing-chamber, a distributor consisting of a disk having radial peripheral vanes through which the gas from the chamber escapes and by which it is directed against the upper part of the coil, and a gauze screen con- 120 125 130

tiguous to the disk through which the gas passes and is burned.

6. The combination in a hydrocarbon-burner of a vertical chamber having an inlet and jet at the lower part, and discharge at the top, a coil surrounding said chamber having its upper portion exposed above the top, means for admitting the hydrocarbon to the lower part of the coil, means for conducting the resultant gas from the upper part of the coil to the burner, a disk having vanes around its periphery through which the combustible gas escapes and by which it is directed against the coil, a branch conductor through which a portion of the gas is transmitted and a circular heater located below the coil into which said gas is admitted and by which the heat of the

coil is maintained when the main burner is out of service.

7. The combination in a hydrocarbon-burner of a central mixing-chamber, means for admitting vapor and air into the lower part, a heating-coil surrounding the mixing-chamber, means for supplying hydrocarbon liquid to be vaporized in the coil and conducting it to the mixing-chamber, a vertically-adjustable distributor, and a central tubular support therefor.

In witness whereof I have hereunto set my hand.

EDGAR B. BADLAM.
